MARIUS LATOUR

By his Attorney
Dra. J. Adams

UNITED STATES PATENT OFFICE.

MARIUS LATOUR, OF PARIS, FRANCE, ASSIGNOR TO LATOUR CORPORATION, OF JERSEY CITY, NEW JERSEY, A CORPORATION OF DELAWARE.

RADIO SIGNALING APPARATUS.

Application filed August 19, 1921, Serial No. 493,668, and in France July 30, 1917.

(GRANTED UNDER THE PROVISIONS OF THE ACT OF MARCH 3, 1921, 41 STAT. L. 1313.)

This invention has references to an improvement in or modification of the invention claimed in my prior application, U. S. Serial No. 209,269, now Patent No. 1,405,523, and relates to the adaptation of the amplifying arrangement described in the above specification to the reciprocal connections for telephonic transmission.

For a complete description of my invention reference is made to the accompanying drawing in which Fig. 1 is a diagrammatic showing of a two valve amplifying arrangement according to my invention; Fig. 1^a is a modification of Fig. 1 showing the use of transformers in the amplifier inlet and outlet; Fig. 2 shows one form of the exit transformer used in Fig. 1; Fig. 3 shows a modification of the exit transformer; Fig. 4 shows a still further modification of the exit transformer.

In Figure 1 this adaptation is illustrated. As was set forth in the main application, the amplifying arrangement comprises lamp relays 1, comprising plates 2, grids 3 and filaments 4 heated by means of the source 5. The plate circuits are supplied with current by the battery P. The current to be amplified is led into the primary of the transformer T₁, the secondary of which supplies current to the grid-filament circuit of the first lamp. The transformer T₂ serves to transmit the amplified current to the second lamp. The current as amplified is supplied in series to the telephone line L₂, by the secondaries S₁, S₂, S₃, S₄ of the transformer T₂. The primary of the transformer T₁ is connected as a shunt to the line between the points a, b, which represent the mid points of the secondaries S₁, S₂, S₃, S₄.

In order that there may be no singing but good amplification, nevertheless it is necessary to equalize, as far as possible, the impedances of the eastern and western sides of the line L₁, L₂. This is effected by putting resistances, inductances and capacities of suitable values (or any combinations of these elements) in series or as a shunt on the eastern or western side (or on both at the same time) of the line L₁, L₂.

The precautions already indicated in the parent specification and the additions thereto (defining the potential of the masses M₁, M₂, M₃ of the transformers, of the primary

winding of the transformer T₁, of the earth, etc.) are also taken.

In the event of the asymmetry of the impedances on the eastern or western sides of the line being too great, different numbers of turns might be admitted for the secondaries S₁, S₂, S₃ and S₄, the side of smaller impedance requiring the smaller number of turns.

Experience shows that for the construction of the transformers T₃ good results are obtained by constructing the secondaries S₁, S₄ and S₂, S₃ of coils located on both sides of the primary, in such a way that the primary of the transformer T₃ occupies a central position. The secondaries S₁, S₄ and S₂, S₃ are wound together, the winding being effected with two wires in hand.

In Figure 2 the exit transformer T₃ is shown alone. An adjustable resistance R has been shown as a shunt to the terminals of the primary of this transformer, and adjustable resistances R₁ and R₂ connected diagonally to the terminals of the secondaries S₁, S₂, S₃, S₄ of the same transformer. The object of the arrangement of these resistances is to prevent singing by tending to establish automatic balancing of the eastern and western sides of the line L₁, L₂.

It will in fact be observed that only an asymmetry can make amplified current flow in the diagonal resistances R₁ and R₂. The asymmetry therefore tends to damp the amplification when occasion arises, that is to say, when this asymmetry would tend to cause singing. Instead of the resistance R, or in series with it, a testing receiver might be inserted, which would enable the working of the telephone line to be judged and would make it possible to observe whether there is any singing taking place. Under certain conditions, any suitable impedances may be substituted for the resistances R, R₁, R₂ indicated in Figure 2.

In Figure 3 another automatic process for balancing the impedances has been shown obtained by means of a special separate self induction coil. This self-induction coil comprises four windings S_{1a}, S_{2a}, S_{3a}, S_{4a}, shunted by means of resistances R_{1a}, R_{2a}, R_{3a}, R_{4a} and these same windings being preferably without leakage between them. Windings S_{1a} and S_{3a} are inserted between the eastern side

of the telephone line and one side of amplifier transformer, and windings S_{2a} and S_{4a} are inserted between the western side of the line and the other side of amplifier transformer, the windings being connected in such a manner as to produce no flux when the eastern and western line currents are equal. Under these no-flux conditions there will be but a negligible voltage across each of the windings S_{1a} , S_{2a} , S_{3a} and S_{4a} , and hence practically no current through the damping resistances R_{1a} , R_{2a} , R_{3a} , and R_{4a} in shunt thereto. But as soon as the eastern and western sides of the line are traversed by current of different intensities there is a resulting magnetic flux and currents flow in the resistances R_{1a} , R_{2a} , R_{3a} and R_{4a} , and these currents tend to reestablish symmetry.

20 With regard to this figure it is to be noted that unlike the preceding figures the windings concerned form no part of the transformer, but constitute rather a special self-induction coil.

25 Another arrangement is illustrated in Figure 4. In this arrangement the transformer T_3 is divided into independent transformers, so constructed as only to take very little magnetizing current. The equality of 30 the currents tends this time also to be produced automatically on the eastern and western sides of the line.

In Figure 1 a two-lamp amplifying arrangement has been shown, but the invention 35 extends of course to cases in which only a single relay lamp is employed, or any number of relay lamps.

The invention may be applied also to circuit arrangements in which the amplifying 40 system is supplied with current in series on the telephone line instead of being fed in shunt of this line as shown in Fig. 1, and in accordance with which the amplified current has its exit in shunt of the telephone line, instead of having its exit in series as shown in Fig. 1.

The patent referred to above discloses an arrangement of telephone amplifiers for deforming the voice, the effect of which is 50 counteracted by the deformation caused by the telephone line whereby the use of lines without Pupin coils is feasible.

55 Preferably, such amplifiers will be constructed with transformers supplied with a strong magnetizing current (e. g. air gap transformers), and the primary or secondary windings of which are shunted by capacities adapted to compensate the magnetizing current for the highest frequency of the telephone currents.

60 Under these conditions, the harmonics will be automatically reinforced.

65 For the same purpose, it is advisable to reduce the magnetic leakages between the primary and secondary windings by locating

the primary in the centre of the secondary or vice versa. The weakening effect of the leakage inductances will be felt the more, the higher the frequency.

Amplifiers may be distributed over sufficiently long lines and depending on their connection with the line, these amplifiers will either increase the resistance of the line, or compensate the losses. In this manner, the deformation usually introduced by the line 75 will be avoided.

The inlet and the outlet of the amplifier shown in Fig. 1 at L_1 and L_2 may be effected with the interposition of transformers, in a manner to reduce the crackling sound of the 80 line as shown in Fig. 1^a. The middle points of the windings of these transformers may be connected together and the potential of this common connection may be defined to 85 reduce the probability of arcing.

Having described my invention, what I claim is:

1. In an amplifying system, two sections 90 of telephone conductors, a transformer having a primary winding and secondary windings, said secondary windings telephonically connecting the sections of telephone conductors, amplifying means having an input circuit and an output circuit, said input circuit being connected to points intermediate the 95 ends of said secondary windings, said primary winding functioning to connect inductively said output circuit to said secondary windings, and resistances connected across said windings to compensate automatically 100 for differences in impedance between said sections.

2. In an amplifying system, two sections 105 of telephone conductors, a transformer having a primary winding and secondary windings, said secondary windings telephonically connecting the sections of telephone conductors, amplifying means having an input circuit and an output circuit, said input circuit being connected to points intermediate the 110 ends of said secondary windings, said primary winding functioning to connect inductively said output circuit to said secondary windings, and means including two resistances to compensate automatically for differences in impedance between said sections, one of said resistances being connected between one side of one section and the remote side 115 of the other section, and the other resistance being connected between the other two sides 120 of said sections.

3. In an amplifying system, two sections 125 of telephone conductors, a transformer having a primary winding and secondary windings, said secondary windings telephonically connecting the sections of telephone conductors, amplifying means having an input circuit and an output circuit, said input circuit being connected to points intermediate the 130 ends of said secondary windings, said pri-

mary winding functioning to connect inductively said output circuit to said secondary windings, and means including resistances for compensating automatically for differences in impedances between said sections, one resistance being connected between the terminal of one secondary winding and a remote terminal of the other secondary winding and the other resistance being connected between the other terminals of said secondary windings and a resistance connected in shunt of said primary winding. 10

MARIUS LATOUR.
